US0D1105976S

(12) **United States Design Patent** (10) Patent No.: **US D1,105,976 S**
(45) Date of Patent: ** Dec. 16, 2025

(54) **SUSPENSION UNIT FOR SNOWMOBILE**

(71) Applicant: **Aurora Powertrains Oy**, Rovaniemi (FI)

(72) Inventors: **Olli Haavikko**, Rovaniemi (FI); **Jori-Jaakko Niskanen**, Rovaniemi (FI); **Matti Autio Niemi**, Rovaniemi (FI)

(73) Assignee: **Aurora Powertrains Oy**, Rovaniemi (FI)

(**) Term: **15 Years**

(21) Appl. No.: **30/015,464**

(22) Filed: **Jul. 29, 2025**

Related U.S. Application Data

(62) Division of application No. 29/909,733, filed on Aug. 10, 2023, now Pat. No. Des. 1,090,343.

(57) **CLAIM**

The ornamental design for a suspension unit for snowmobile as shown and described.

DESCRIPTION

FIG. 1 is a front elevational view of a suspension unit for snowmobile;

FIG. 2 is a rear elevational view of the design shown in FIG. 1;

FIG. 3 is a top plan view of the design shown in FIG. 1; FIG. 4 is a bottom plan view of the design shown in FIG. 1; FIG. 5 a right side elevational view of the design shown in FIG. 1; and,

FIG. 6 is a left side elevational view of the design shown in FIG. 1.

The broken lines shown in the drawings form no part of the claimed design.

1 Claim, 6 Drawing Sheets
